UNITED STATES PATENT OFFICE

BRYAN P. JOYCE, OF DAVENPORT, IOWA

DIAPHRAGM ASSEMBLY

Original application filed November 5, 1925, Serial No. 67,140. Divided and this application filed April 14, 1927. Serial No. 183,749.

This application is a division of my U. S. application Serial No. 67,140, allowed March 22, 1927, Patent No. 1,640,606 dated August 30, 1927.

5 The present invention relates to improvements in diaphragm assemblies which, while designed primarily for use in connection with liquid level gauges, are not restricted to such use.

10 It is the object of the invention to provide a new and improved relation of casing-forming disks and diaphragm, in which the peripheral edge of one disk is clinched around the peripheral edge portions of the diaphragm 15 and the other disk, so that the three disks may be fluid-tightly connected in a single operation.

With the foregoing in view, the invention resides in the novel subject matter hereinafter 20 described and claimed, the description being supplemented by the accompanying drawing.

Fig. 1 is a sectional view through a diaphragm assembly constructed in accordance with my invention.

25 Fig. 2 is a bottom plan view of the parts shown in Fig. 1.

In the drawings above briefly described, the numeral 3 designates a relatively small disk which is of substantially rigid nature although the metal or other material from which it may be formed, will of course yield to some extent. At one side of this disk 3, is a diaphragm 4 of no greater diameter than said disk, said diaphragm being preferably 35 formed from thin sheet metal. At the side of the diaphragm 4, remote from the disk 3, is a relatively large disk 5, of the same characteristics as the disk 3 with regard to material, sheet metal being preferably used for 40 both of said disks 3 and 5. The disk 5 is of considerably greater diameter than the disk 3, and its peripheral edge portion 6 is clinched around the corresponding portions of said disk 3 and diaphragm 4 thereby fluid-tightly 45 uniting the three disks and providing a permanently assembled construction. If desired, the three disks may be laterally stamped in the same direction on continuous lines as indicated at 7, providing interengaged ribs and

grooves to even more advantageously anchor the diaphragm between the disks 3 and 5.

The diaphragm assembly, so far described, may be used wherever applicable, and in most adaptations, it will be required that the movement of the diaphragm 4 be limited in both directions. To attain this end, the body portions of the disks 3 and 5 may be spaced apart the desired distance to permit the necessary movement of the diaphragm, but to solidly engage the latter in either of its extreme positions. By preference, the disk 3 is flat and the disk 4 bowed away from said disk 3, to obtain the necessary space within which the diaphragm operates. For sake of clearness in the illustration the amount of bow of the disc has been exaggerated. Actually, the space between the discs 3 and 5 is but a few hundredths of an inch, permitting the diaphragm 4 to be stretched or flexed into engagement with said discs over substantially its entire area, the liquids upon both sides of the diaphragm serving as cushions, preventing unnecessary wear of the diaphragm.

For purposes of illustration, a gauge glass 75 8 is suitably connected at 9 with the upper disk 5 and said glass will contain an indicating liquid. For a similar purpose, a tube 10 is shown connected by an appropriate coupling or the like 11 with the disk 3, and in most instances, the tube, the coupling and the portion of the casing below the diaphragm 4, will contain liquid which is moved by means forming no part of the present invention, to in turn move the diaphragm 4, thus raising or 85 lowering the column of liquid in the gauge glass 8, as the case may be.

I claim:

1. A diaphragm assembly comprising a pair of disks secured together in fluid tight relation and having a thin resilient diaphragm clamped between their edges, said diaphragm being subject to liquid pressure upon both sides and having a shape such that it may be flexed into engagement with substantially the entire surface of the opposed faces of the disks to permit said liquid to cushion the diaphragm in its movement toward either disk.
2. In a diaphragm assembly, a relatively 100

small disk, a diaphragm at one side of said disk and of no greater diameter than the latter, a relatively large disk at the side of said diaphragm opposite said small disk, the 5 peripheral edge of said large disk being turned laterally across the peripheral edges of said diaphragm and said small disk and clinched inwardly against said small disk, thereby holding the peripheral portions of 10 said disks and diaphragm in tight contact with each other, said small and large disks being spaced apart except at said peripheral portions to permit movement of the diaphragm and each having an opening serving 15 as a fluid inlet and outlet, said peripheral portions of the disks and diaphragm being stamped longitudinally in the same direction on continuous lines to provide interengaging ribs and grooves insuring tight connection of 20 said disks and said diaphragm with each other.

3. A diaphragm assembly comprising a relatively small disk, a diaphragm at one side of said disk and of no greater diameter than 25 the latter, and a larger disk at the side of the diaphragm remote from the relatively small disk, the edge portion of the larger disk being clinched around the edge portions of the other disk and the diaphragm to tightly se- 30 cure the disks and diaphragm together, the body portions of said relatively small disk and said larger disk being spaced apart slightly to permit a small amount of movement of the diaphragm, the diaphragm dividing the 35 space between the disks into two liquid cham- bers, each having an inlet for liquid, and a liquid conductor connected to each inlet in liquid tight relation, said diaphragm being subject to liquid pressure upon both sides and 40 having a shape such that it may be flexed into engagement with substantially the entire sur- face of the opposed faces of the disks to per- mit said liquid to cushion the diaphragm in its movement toward either disk.

45 In testimony whereof I have hereunto affixed my signature.

BRYAN P. JOYCE.
